TANDEM COMPOUND ELASTIC FLUID
TURBINE ARRANGEMENT

Glenn B. Warren, Schenectady, N. Y., assignor
to General Electric Company, a corporation of
New York

Application November 1, 1943, Serial No. 508,588

1 Claim. (Cl. 253—69)

The present invention relates to tandem compound elastic fluid turbine arrangements having high pressure and low pressure turbines or turbine parts with a single shaft supported near the ends of the turbine arrangement and at one or more intermediate points. Such arrangements are generally used when it is desired to produce considerable load output of the order of 50,000 kw. or more on a single shaft. Such shaft may be of one piece or in several sections aligned and rigidly fastened together. Difficulties have heretofore been experienced with the alignment of the bearing or bearings for supporting intermediate shaft portions. Another drawback of these arrangements is the great friction loss incurred in present crossover conduits for conducting elastic fluid discharged from the high pressure part to the low pressure part or parts of such tandem compound steam turbine arrangements.

The object of my invention is to provide an improved construction of turbine arrangements of the type above specified whereby the aforementioned difficulties are materially reduced.

For a consideration of what I believe to be novel and my invention, attention is directed to the following description and the claim appended thereto in connection with the accompanying drawings.

In the drawings Fig. 1 illustrates a tandem compound turbine arrangement embodying my invention in which the low pressure part is in the form of a single flow turbine, and Fig. 2 is a modification of my invention in which the low pressure part is in the form of a multiple flow, more specifically a triple flow turbine. Figure 3 is a sectional view on line 3—3 of Figure 1.

The arrangement of Fig. 1 comprises a high pressure turbine 10 and a low pressure turbine 11. The high pressure turbine 10 has an inlet conduit 12 for conducting elastic fluid to the turbine and valve means 13, 14 for controlling the flow of elastic fluid through the turbine. The valves are not shown in detail because they do not form a particular part of my invention. The turbine has an outer casing 15 and an inner casing 16 suitably supported on the outer casing. The rotor includes a shaft or shaft section 17 with a plurality of bucket wheels 18 fastened thereto. Elastic fluid is directed to successive wheels by nozzle diaphragms 19 disposed between the wheels and supported on the inner casing 16.

Similarly, the low pressure turbine includes an outer casing 20, a rotor having a shaft or shaft

section 21 aligned with the shaft section 17 and rigidly secured thereto and carrying a plurality of bucket wheels 22. Fluid discharged from the last bucket wheel 18 of the high pressure part is conducted to the first wheel of the low pressure part 11 by means including a diaphragm or fluid guide and directing device 23. Fluid is conducted from the first bucket stage wheel 22 to the succeeding bucket wheels by means of other suitable fluid guide and directing means or diaphragms 24 disposed between adjacent wheels 22 and suitably supported on the casing 20.

The bearing means for supporting the single shaft with the sections 17, 21 comprises the usual bearings 25 and 26 provided near the high pressure end and low pressure end respectively of the tandem compound turbine arrangement. In addition to the bearings 25, 26 I provide other bearing means for supporting an intermediate portion or portions of the single shaft. These other bearing means according to my invention are completely enclosed in the turbine shell or casing and have an outer bearing casing which forms part of a channel for conducting elastic fluid from the high pressure to the low pressure part of the turbine arrangement.

In the present instance I have shown a single bearing 27 for supporting an intermediate portion of the shaft 17, 26 between the high pressure part 10 and the low pressure part 11. The bearing 27 has an inner casing or bearing member 28 supported on and enclosed within an outer bearing casing 29. The latter has end walls sealed to the respective shaft sections 17, 21 by means of packings 30 and 31 respectively. One end portion of the outer bearing casing 29 has an annular projection 32 forming part of the first stage diaphragm 23 and having a tongue and groove connection with an outer nozzle forming part of such diaphragm. Thus, the outer bearing casing 29 constitutes a means for positioning and supporting the first stage diaphragm or annular fluid directing and guiding means for the low pressure turbine part. End portions of the inner and outer bearing casings are sealed together by means including annular flexible sealing rings 33, thus forming a ring chamber between the two bearing casings. This chamber is connected to conduits 34 and 35 through which air or like cooling medium may be circulated through the chamber during operation to maintain the inner bearing casing relatively cool. The bearing as a whole is supported on the turbine casing or shell, in the present instance on a flanged cylindrical extension 36 of

the low pressure casing 20. Diametrically opposite portions of the outer bearing casing 29 have horizontal projections or arms 37 held in recesses 38 formed in webs 39 of the cylindrical turbine casing extension 36. In addition the outer bearing casing 29 is guided on the extension 36 by means including vertical projections or arms 40 on the bearing casing cooperatively associated with corresponding projections 41 on the extension 36 of the turbine casing. Thus the bearing 10 is loosely held and centered on one of the turbine casings or an extension thereof between successive turbine stages. The extension 36 and the outer casing 29 of the bearing form an annular channel for conducting elastic fluid from the high pressure part 10 to the low pressure part 11. This annular channel produces little friction loss as compared with the usual type of crossover conduit.

In the arrangement of Fig. 2 the tandem compound turbine comprises a high pressure part 50 corresponding to the high pressure part 10 of Fig. 1 and a low pressure part 51 which is of the multiple flow, more particularly the triple flow type. This triple flow, low pressure turbine comprises a single flow part 52 corresponding to the single flow, low pressure part 11 of Fig. 1 and a double flow part 53 arranged in parallel with the single flow part 52.

The low pressure parts 52, 53 are arranged in alignment with the high pressure part 50, the single flow part 52 being interposed between the high pressure part 50 and the double flow part 53, the axial direction of fluid flow being the same in the high pressure part 50, the single flow part 52, and the outer half of the double flow part 53, the flow through the inner half of the double flow part being axially in opposite direction. The high pressure part 50 has a casing 54 with an inlet 55 and control valve means 56, 57. The low pressure parts 52, 53 have casings 58 and 59 respectively enclosed within a common exhaust hood 60. Elastic fluid discharged from the high pressure part is conducted to the low pressure part by means of a substantially cylindrical extension 61 of the high pressure casing 54. This extension conducts fluid from the last stage of the high pressure part 50 directly to the single flow part 52. An upper portion of the extension 61 has a circumferentially extending opening 62 connected by means including a crossover conduit 63 to the inlet of the double flow part 53. The inner wall of the crossover conduit 63 is formed by a part of the exhaust hood 60.

The high pressure part 50 has a shaft section 64 and the low pressure part 52, 53 has a shaft section 65 forming together a single shaft which in the present instance is supported by means of four bearings, a bearing 66 near the high pressure end of the arrangement, a bearing 67 near the low pressure end of the arrangement, and two bearings 68 and 69 associated with spaced intermediate portions of the shaft 64, 65. The bearing 68 is located between the outlet of the high pressure part 50 and the inlet of the single flow, low pressure part 52, and the bearing 69 is located between the single flow, low pressure part 50 and the double flow, low pressure part 53. Each of the bearings 68, 69 has inner and outer casings with the inner casing suitably supported on the outer casing and the outer casing in turn supported on the exhaust hood by means including an axially extending web 70 welded or suitably secured to the exhaust hood 60 and the extension 61, and stiffening ribs 71 between the web 70 and the hood 60. The bearing 68 in this arrangement does not constitute a support for the first stage diaphragm of the single flow part 52. Otherwise the bearing may be constructed similarly to the intermediate bearing 27 in Fig. 1.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent of the United States is:

In a large capacity tandem compound elastic fluid turbine, a single casing containing a high pressure part and a low pressure part, each having a plurality of turbine stages with the entrance to the low pressure part closely adjacent and directly facing the exit from the high pressure part, a single shaft for both parts, and bearing means in the casing including a bearing supporting a shaft portion between the exit of the low pressure part and the inlet of the high pressure part, said bearing having an outer casing within and spaced from the turbine casing and forming therewith a substantially unobstructed annular passage short in length and large in cross-sectional area for conducting elastic fluid from the exit of the high pressure part directly to the inlet of the low pressure part with a minimum of friction losses.

GLENN B. WARREN.
